UNITED STATES PATENT OFFICE.

IGNATI A. CZAVRA, OF ROCHESTER, NEW YORK.

AUTOMATIC GUN.

1,321,419.

Specification of Letters Patent. Patented Nov. 11, 1919.

Application filed September 18, 1918. Serial No. 254,571.

To all whom it may concern:

Be it known that I, IGNATI A. CZAVRA, a citizen of Russia, residing at Rochester, in the county of Monroe and State of New York, have invented certain new and useful Improvements in Automatic Guns; and I do hereby declare the following to be a full, clear, and exact description of the same, reference being had to the accompanying drawings, forming a part of this specification, and to the reference-numerals marked thereon.

My invention relates to automatic guns and has for its object to provide a gun of this kind, which is simple in construction, light and which can be carried and operated without interfering with other activities of the operator. A further object of the invention is to provide an automatic gun which can be carried upon the breast of the operator without the use of his hands and which can be securely locked against accidental discharge when not in use. To these and other ends the invention consists in certain improvements and combinations of parts, all as will be hereinafter more fully described, the novel features being pointed out in the claims at the end of the specification.

30 In the drawings:

Figure 1 is a front elevation of a gun constructed according to my invention with the cover removed to show the underlying mechanism,

35 Fig. 2 is a similar view with parts broken away and shows parts in other relations.

Fig. 3 is an enlarged central vertical section taken on the line 3*-3* of Fig. 4,

40 Fig. 4 is a front elevation of the device with the cover in position thereon,

Fig. 5 is a section on the line 5*-5* of Fig. 3, and

45 Fig. 6 is a sectional detail view, showing the mounting of the revolving cylinder and its bearings.

Similar reference characters in the several figures indicate the same parts.

My gun comprises a support 1 in the form of a metallic plate which is adapted 50 to be carried against the breast of the operator. Hinged at the sides of the plate 1, as at 2, are flexible extensions 3 and 4, to which are secured straps 5, which may be tightly buckled about the body of the operator by means of buckles 6. Secured to the top of the plate 1 are straps 7 which pass

over the shoulders of the operator and engage with the buckles 8. By this construction, the plate 1, upon which the mechanism is supported, may be securely fastened to 60 the body of the operator and carried without the use of his hands, or interfering with the free movement thereof. Mounted upon the plate 1 slightly above the center thereof is a bearing plate 9 secured to the plate 65 1 by screws 9^a or other suitable means. The plate 9 is cylindrical in form and has a central aperture 10 extending at substantially right angles to the supporting plate 1. The bearing plate 9 is also provided 70 with a horizontally extending opening 11, which intercepts the aperture 10. A cartridge carrier or cylinder 12 having a plurality of chambers 13 for cartridges, and a diameter substantially equal to the diameter 75 of the bearing plate is mounted to revolve in contact with the bearing plate 9. The cylinder 12 is adapted to be inserted and removed from the instrument as a unit, and the chambers 13 are arranged concentrically near its periphery, 8 chambers being shown in the present instance. The cylinder has a central aperture 14 extending therethrough. Mounted in the aperture 14 is a bearing bolt 15 having an enlarged end 16 and a threaded outer end 17. Cooperating 80 with the threaded outer end 17 is a nut 18 which is adapted to lie within a counterbored part of the cylinder and engages a shoulder formed in the bottom thereof. The cylinder is adapted to rotate freely on the bolt 15, and the cylinder and bolt are 85 inserted as a unit, the enlarged head 16 being seated in the central aperture in the bearing plate 9. The part 16 has an aperture 20 therethrough adapted to receive a locking pin 21, which passes through the opening 11 in the bearing plate and through the opening 20 in the bolt 15 and securely locks the bolt 15 and the cylinder to the 90 bearing plate 9. In order to secure proper alignment of the openings 11 and 20, the head 16 of the bolt 15 may be provided with a groove to coöperate with a projecting lug 22 formed in the side of the aperture 10. The pin 21 may be provided with a finger piece 23 to facilitate insertion and removal thereof, and a resilient locking arm 24 pivoted to the plate 1 and having a detent 25 co-operating with the apertures 25^a in the 95 plate 1 may be employed to lock the pin 21 in position. The outer end of the bolt 15 100

may be provided with a conical shaped opening or aperture 24^a adapted to coöperate with a centering pin 25^b on a sheet metal cover 26 hinged at 27 to the supporting plate 1 and adapted to be locked in the position shown in Figs. 3 and 4 by locking devices 28. A discharge barrel 29 is also carried by the plate 26, and when the plate 26 is in the operative position shown in Fig. 10 3, the barrel 29 is brought into proper alignment with that chamber of the cylinder in firing position by means of the centering pin 25.

Means are provided for rotating the cylinder 12 to successively bring the chambers carrying the cartridges into firing position. Said means comprises a ratchet wheel 29 comprising a plurality of teeth formed upon the sides of the base of the cylinder 12 and 15 integral therewith. The number of teeth 29 corresponds to the number of chambers in the cylinder. Coöoperating with the teeth 29 of the ratchet wheel is a star wheel 30. Formed integral with or riveted to the face 20 of the star wheel 30 is a ratchet wheel 31, and the combined star wheel and ratchet wheel are pivoted upon the face of the plate 1. Pivoted concentrically with the star wheel 30 is a bell crank lever 32 having a 25 pawl 33 pivoted on its shorter arm 34. The pawl 33 is adapted to successively engage the teeth of the ratchet wheel 31, as the lever is vibrated. A spring 35 on the bell crank lever coöperates with the pawl to resiliently 30 hold it engaged with the teeth of the ratchet wheel. A spring 36 secured to the plate 1 coöperates with the longer arm of the bell crank lever and normally holds the bell crank lever in the retracted position shown 35 in Fig. 1 of the drawings. To prevent free movement of the wheel 30 and to prevent its being moved in a reverse direction by the pawl 33, a detent pawl 37 is pivoted to the plate 1 and coöperates with the teeth of the 40 ratchet wheel 31. A spring 38 resiliently holds the pawl 37 in engagement with the ratchet wheel. Stops 39 and 40 project from the face of the plate 1 and coöperate with the lever 32 to limit its motion in opposite 45 directions. The lever 32 is operated by means of a flexible cord 41 secured to the end of the longer arm of the lever and passing over anti-friction guide rollers 42, 43 and 44, from the latter of which it extends upwardly, and at its upper extremity is provided with a wrist band 45 adapted to be secured to the arm of the operator. The cord 41 above the guide roller 44 has a lock bolt 46 connected in the cord and guided in 50 a plate 47 secured to the member 4. A locking arm 48 is pivoted to the member 47 and coöperates with the bolt 46 to prevent actuation thereof while the instrument is not in use. It will be noted that this locking means is 55 adapted to effectively prevent operation of

the parts while the gun is out of use. By a movement of the arm, the bell crank lever 32 is vibrated to rotate the cylinder to successively bring the cartridges contained therein into firing position. The arms of the star 70 wheel 30 also coöperate with a firing hammer 49 which actuates devices for firing cartridges as they are successively brought into the firing position. The hammer 49 is pivoted at 50 to the supporting plate 1 and 75 is provided with a spring 51 resiliently holding the hammer in the position shown in Fig. 1. The spring 51 also actuates the hammer to discharge the gun. The hammer 49 has a depending arm 52 in the path of the 80 arms of the star wheel 30. When the star wheel 30 is rotated, these arms successively engage the arm 52 and retract the hammer to the position shown in Fig. 2. A slight forward movement of the arms 30 from the 85 position shown in said figure releases the hammer which is moved to discharge the gun by the spring 51. Depending from the hammer 49 adjacent its end is a beveled or wedge shaped lug or projection 53 adapted 90 to coöperate with a slide 54 which carries the firing pin 55. By references to Figs. 3 and 6 it will be noted that the slide 54 is beveled to coöperate with the lug 53 and a spring 55^a surrounds the firing pin and 95 serves to hold the same in retracted position, as shown in Fig. 6. The slide 54 has a bearing in a cut out portion 56 in the upper side of the bearing plate 9.

Means are provided for locking the hammer in the position shown in Fig. 1, while the gun is out of use. This means comprises a locking pin 57 slidably mounted in a housing 58 secured to the supporting plate 1. A spring 59 serves to project the bolt to locking position. The end of the bolt 57 is provided with an eye to which a flexible cord 60 is secured, and which passes over a plurality of roller guide bearings 61, and at its outer end is provided with a wrist band 62 105 which may be secured to the arm of the operator. If desired, means may be provided such as shown at 63 for adjusting the lengths of the cords 41 and 60. This means comprises screws 64 secured to the cords and 110 connected with threaded openings at the ends of a coupling member 65.

It will be noted that the cover 26 which houses the parts is comparatively shallow and beveled at its outer edges, making the 115 instrument very compact.

The operation of the device is as follows: The cylinder 12 having its chambers 13 filled with loaded cartridges, together with the bearing bolt 15, is inserted, the head 16 of 120 the bolt entering the opening 10 in the path 9. The chambers of the cylinders may be counterbored as indicated in the drawings, so that the cartridges may lie flush with the inner surface of the cylinder. The pin 21 130

is then inserted to lock the bolt 15 and cylinder to the bearing plate 9. The cover 26 is now moved to closed position, the pin 24 operating to properly align the barrel 5 with that chamber of the cylinder which is in firing position. In order to prevent a too free rotation of the cylinder, a spring 66 may be secured to the cover 26 in position to frictionally engage the cylinder. The 10 operator now moves the arm to which the hand 62 is attached to withdraw the bolt 57 from locking position. With the locking member 48 in released position, the operator now moves his arm to pull the cord 41, to 15 swing the lever 32 against the tension of its spring from engagement with the stop 39, to engagement with the stop 40 and the ratchet and star wheels forward one tooth. During this movement, the star wheel first 20 engages and rotates the cylinder forwardly, and after a slight movement of the cylinder, engages the projection 52 of the hammer, raising the same as the cylinder is moved forward. Simultaneously with the alignment 25 of the succeeding chamber with the barrel and firing pin, the star wheel passes the lug 52 and the spring 51 swings the hammer into engagement with the slide 54, and the aligned cartridge is discharged. The 30 bands 45 and 62 may be attached to the arms above the elbows, as only a slight movement of the cords is required to operate the gun, thus leaving the forearms and hands free.

35 Having described my invention, what I claim and desire to secure by Letters Patent is:

1. In an automatic gun, the combination of a plate adapted to be secured to the body 40 of the operator, a cartridge cylinder supported thereon to revolve about an axis substantially perpendicular to the face of the plate, a firing hammer pivoted to said plate for movement substantially parallel therewith, and a revolute star wheel adapted to rotate the cylinder and simultaneously retract said hammer.

2. In an automatic gun, the combination of a support, a cartridge cylinder thereon 50 revolute about an axis substantially perpendicular thereto, a firing hammer pivoted to said support for movement substantially parallel therewith, a ratchet wheel on said cylinder, and a revolute star wheel for retracting said hammer and adapted to engage the teeth of said ratchet wheel to rotate the same.

3. In an automatic gun, the combination of a support, a cartridge cylinder revolubly 60 supported thereon, a firing hammer pivoted to said support, a revolute star wheel for rotating said cylinder and retracting said hammer, and pawl and ratchet devices for rotating said star wheel.

65 4. In an automatic gun, the combination

of a support, a cartridge cylinder revolubly supported thereon, a firing hammer pivoted to said support, a revolute star wheel for rotating said cylinder and retracting said hammer, a ratchet on said star wheel, and 70 a pawl coöperating with said ratchet for imparting a step by step movement to said star wheel.

5. In an automatic gun, the combination of a support, a cartridge cylinder thereon 75 revolute about an axis substantially perpendicular thereto, a firing hammer pivoted to said support for movement substantially parallel thereto, means for revolving said cylinder and simultaneously retracting said 80 hammer and means for locking said hammer against actuation.

6. In an automatic gun, the combination of a supporting plate, a bearing plate mounted thereon, a revolute cylinder 85 detachably mounted on said bearing plate, a slide having a beveled surface and a firing pin mounted in a recess in said bearing plate, a hammer pivoted to said supporting plate and having a beveled projection for 90 engaging the beveled surface on said slide for actuating the slide, and means for actuating said hammer and rotating the cylinder.

7. In an automatic gun, the combination of a supporting plate, means for securing 95 said plate to the body of the operator, a carrier for a plurality of cartridges supported on said plate, a firing pin, a hammer pivoted to said plate and adapted to coöperate with said firing pin, and means adapted to be 100 secured to the arm of the operator for moving said carrier to successively move the cartridges into alignment with said firing pin and simultaneously actuate the hammer.

8. In an automatic gun, the combination 105 of a supporting plate, means for securing said plate to the body of the operator, a carrier for a plurality of cartridges supported on said plate, a firing pin, a star wheel for moving said carrier to move the cartridges 110 successively into alignment with said firing pin and actuate the firing pin, and pawl and ratchet devices for actuating the star wheel.

9. In an automatic gun, the combination 115 of a supporting plate, means for securing said plate to the body of the operator, a carrier for a plurality of cartridges supported on said plate, a firing pin, a cover plate on said supporting plate, a discharge barrel on said cover plate in alignment with said firing pin, and means for moving said carrier to successively bring a cartridge into alignment with said barrel.

10. In an automatic gun, the combination 125 of a supporting plate, means for securing said plate to the body of the operator, a cylinder having a plurality of chambers revolubly mounted on said plate, a firing pin in alignment with one of the chambers of said cylinder, a cover plate hinged to said sup- 130

porting plate, a discharge barrel on said cover plate, means for alining said barrel with that chamber of the cylinder in alinement with the firing pin, and means for 5 rotating the cylinder to successively bring its chambers into alinement with the firing pin.

11. In an automatic gun, the combination of a support adapted to be secured to the 10 body of the operator, a cartridge container revolvably mounted on said support with an axis substantially normal to the latter, container revolving means on said support, a hammer on said support, said revolving 15 means and hammer being disposed parallel with said support for movement in the plane of the latter, and actuating means for said revolving means and hammer.

12. In an automatic gun, the combination 20 of a support adapted to be secured to the body of the operator, a bearing on said support, a cartridge container revolvable on said bearing about an axis normal to said support, and actuating means on said support 25 arranged for movement parallel with the latter for revolving said container and discharging said cartridges.

13. In an automatic gun, the combination 30 of a support adapted to be secured to the body of the operator, a second support parallel with the first and spaced therefrom, a

revoluble cartridge carrier between said supports, carrier revolving means and firing means between said supports and movable parallel with the latter, and actuating means 35 under control of the operator for said revolving means and firing means.

14. In an automatic gun, the combination of a support adapted to be secured to the body of the operator, a cartridge container 40 revolvably mounted on said support about an axis substantially normal to the latter, a star wheel revoluble in the plane of said support for revolving said container, a hammer movable in the plane of the support for firing said cartridges, and actuating means under control of the operator for revolving said star wheel and moving said hammer.

15. In an automatic gun, the combination 50 of a support adapted to be secured to the body of the operator, a cartridge container revolvably mounted on said support about an axis substantially normal to the latter, a star wheel revoluble in the plane of said support for revolving said container, a hammer 55 movable in the plane of the support for firing said cartridges, and actuating means under control of the operator comprising a pawl and ratchet for revolving said star wheel and moving said hammer.

IGNATI A. CZAVRA.
